UNITED STATES PATENT OFFICE.

SETH CLOVER, OF ERIE, PENNSYLVANIA, ASSIGNOR OF ONE-HALF TO TOBIAS MEYERHOEFER, OF SAME PLACE.

SUCKER-ROD ELEVATOR.

SPECIFICATION forming part of Letters Patent No. 444,332, dated January 6, 1891.

Application filed September 6, 1890. Serial No. 364,143. (No model.)

To all whom it may concern:

Be it known that I, SETH CLOVER, a citizen of the United States, residing at Erie, in the county of Erie and State of Pennsylvania, have invented certain new and useful Improvements in Sucker-Rod Elevators; and I do hereby declare the following to be a full, clear, and exact description of the invention, such as will enable others skilled in the art to which it appertains to make and use the same.

This invention relates to sucker-rod elevators; and it consists in certain improvements in the construction thereof, as will be herein-after fully set forth, and pointed out in the claims.

The invention is illustrated in the accompanying drawings, as follows:

Figure 1 is a perspective view showing the elevator engaged with a sucker-rod. Fig. 2 is an elevation view, on a reduced scale, showing the elevator in position to engage with a sucker-rod.

A is the stock or stem of the elevator-frame, and A' is the fork or yoke at the lower end of the stock. B is the clamp, which is journaled in the yoke A' so it can be turned from the position in Fig. 1 to that shown in Fig. 2—that is, from a horizontal to a vertical position—and a is a lug on the side of the yoke A', which prevents the clamp B from turning clear over, or beyond the two positions shown. When the clamp is in the position shown in Fig. 1, it strikes against the under side of the lug a, and when in the position shown in Fig. 2 it strikes against the side of the lug, so that the clamp, in fact, can move only a quarter-turn on its trunnions.

C is a retaining-bar, which holds the head of the sucker-rod in the jaws of the clamp, as clearly seen in Fig. 1. This bar is pivoted to the stock at c, and it is bent outwardly upward from that point and is formed with a head c' at the upper end.

D is a clip which embraces both the stock A and the retaining-bar C, and is made loose, so as to slide freely on those parts. When the clip is moved up past the pivot c, the upper end of the bar C is drawn in, so as to lie parallel with the stock, and the lower end

thrown out at an angle to the stock, as seen in Fig. 2; but when the clip is drawn below the pivot the retaining-bar is firmly held with the lower end thereof above the space between the jaws of the clamp, so as to safely retain 55 the sucker-rod head in place. When the elevator is drawing out a sucker-rod, it is always in a vertical position, and the clip D is sure to maintain the position shown in Fig. 1.

When the elevator is to be disengaged from 60 the sucker-rod, the slide D is pulled up, and this swings the bar C away from the jaws of the clamp and permits the rod E to escape from the clamp.

I am aware that elevators of this type have 65 been made with a fixed retaining bar or finger and with a vertically-sliding retaining bar or finger, and also with a latch or dog which is pivoted, as in Patent No. 263,820; but none of these prior constructions embrace my invention. 70

What I claim as new is—

1. In a sucker-rod elevator, the combination, with the stock or frame-piece A A' and the clamp B, of the bent retaining-bar C, pivoted to the stock A at c, and a clip embracing both the stock and bar and sliding freely thereon over said pivot, whereby as the clip is moved past the pivot the bar is swung thereon, substantially as and for the purposes 80 set forth.

2. In a sucker-rod elevator, the combination, with the stock or frame-piece A A' and the pivot-clamp B, of the lug a on the part A' near the pivot of the clamp, as shown, whereby the clamp is prevented from turning beyond a horizontal position in one direction and a vertical position in the other direction. 85

3. In a sucker-rod elevator, the combination, with the stock or frame A A', the pivoted clamp B, and a shifting retaining-bar, of a lug on the said frame, which limits the pivotal action of said clamp. 90

In testimony whereof I affix my signature in presence of two witnesses.

SETH CLOVER.
